CONTAINER

John M. Hothersall, Brooklyn, N. Y., assignor to
 American Can Company, New York, N. Y., a
 corporation of New Jersey

Original application August 22, 1931, Serial No.
 558,745. Divided and this application Septem-
 ber 8, 1933, Serial No. 688,680

4 Claims. (Cl. 220—48)

The present invention relates to containers and has for its object broadly improvement in the construction of sheet metal containers adapted to be hermetically sealed and to be readily 5 opened without the employment of tearing keys or other specially provided ripping devices. This is a division of my application Serial No. 558,745, filed August 22, 1931, on Container and method of manufacture.

10 An object of the present invention is the provision of an improved hermetic closure a portion of which may be readily pried loose by any convenient or suitable tool.

15 The invention contemplates the provision of a sunken or annular channel in a can end at the base of which is provided a score line and along which severance may occur by merely inserting a tool in the channel and prying up the central portion of the cover.

20 Another object of the invention is the provision of a can end or cover scored to provide a radially removable part and so constructed and arranged that seaming of the cover to the can body may be accomplished without danger of 25 severing along the score lines.

An important object of the invention is the provision of a container cover of the character described wherein the severable part may be used as a reclosure after opening of the container.

30 Numerous other objects of the invention will be apparent as it is better understood from the following description, which, taken in connection with the accompanying drawing, discloses a preferred embodiment thereof.

35 Referring to the drawing:

Figure 1 is a perspective view of a container and a formed cover embodying the present invention and shown in separated position;

Fig. 2 is a sectional view of the united and 40 closed container and cover illustrating the opening operation wherein the score lines in the cover are about to be broken and a part of the cover about to be removed as by a suitable prying instrument or tool; and

45 Fig. 3 is a view similar to Fig. 2 illustrating the severed cover part in use as a reclosure.

The preferred embodiment of the present invention as illustrated in the drawing comprises a container body 11 preferably outwardly flanged as at 12 (Fig. 1) the body also having a bottom or end 13 secured thereto in any suitable manner as by a double seam 14.

A container cover 15 is provided for closing the container after it has been filled and this 55 cover in its preferred form comprises a drawn

central cup-shaped part 16, the cylindrical or side wall of which is curved preferably S-shaped or in a cyma curve in cross section (Figs. 1 and 2) which is formed by a rounded shoulder part 17 which merges into a relatively smaller inner grooved or curved wall 18, the latter merging into a flat wall 19 substantially parallel to the central part 16 of the cover. The wall 19 along its outer edge merges into a substantially right angled cylindrical wall 21 having a rounded corner 22. 10

The wall 21 of the cover connects with or terminates in an outer flange 23 which is preferably bent downwardly or curled at 24 in the usual manner to condition it for application to the can body. The space between the wall parts 21 and 15 17, 18 constitutes an annular channel 25. An annular weakened score line 26 is cut into the wall 19 at the base of the rounded part 18 and sets off a severable cover part 27 which includes the wall parts 16, 17 and 18. 20

After the container has been filled the cover member 15 is secured in sealing position, the body and cover flange parts 12, 23 being connected in any suitable manner as in a double seam 28 (Fig. 2). During the seaming operation the interfolding of the parts entering into the double seam is accomplished without throwing a strain upon the weakened score line 26 formed in the cover as has been more fully pointed out in my pending application referred 30 to. 25

The usual shipping, storage and distribution may be performed relative to the sealed container and when access to the product is desired, the severable cover part 27 is broken away along 35 the score line 26 and the container is opened. To perform such an opening it is merely necessary to insert the end of any suitable prying tool (designated by the numeral 31 Fig. 2) into the channel 25 of the cover. The tool engages beneath the shoulder 17 as shown and rests upon the rim of the double seam 28 which is then used as a fulcrum. Only a slight prying action of a tool is necessary to tear the severable cover part away from the rest of the cover and along 40 the score line 26 after which it is easily and completely removed to expose the opening bounded by the fractured score line. 45

When desired the severed cover part 27 may be replaced and used as a temporary reclosure. In 50 such use the lower rim or edge of the torn curved wall 18 is inserted within the opening bounded by the broken score line in the remaining cover part, this reclosure position being illustrated in Fig. 3. Such a reclosure is not hermetically tight 55

but answers the purpose required in a reclosure of this character.

It is thought that the invention and many of its attendant advantages will be understood from the foregoing description and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container cover for an easy open container, comprising a drawn central portion having an annular upwardly and outwardly projecting shoulder and an encircling score line formed in the cover adjacent the base of said shoulder, and an annular rim spaced from said shoulder and adapted to be secured to a container body and to support a prying tool which engages under said shoulder above said score line to remove said central portion by tearing along said score line in the opening of said container.

2. A container cover for an easy open container, comprising a drawn cupped portion connected to a surrounding channel section having an encircling score line and being laterally projected into an extending flange, the side walls of said cupped portion being bent into S-shape in cross section and providing an engaging shoulder

for a prying tool when used for severing the said cupped portion from the other parts of the cover by tearing along said score line.

3. A container cover for an easy open container, comprising a drawn cupped portion connected to a surrounding channel section having an encircling score line and being laterally projected into an extending flange which lies substantially in the plane of the central wall of said cupped portion, the side walls of said cupped portion being bent into S-shape in cross section with the base of said walls terminating in said score line and providing an engaging shoulder for a prying tool when used for severing the said cupped portion from the other parts of the cover by tearing along said score line.

4. A container cover for an easy open container, comprising a severable central portion set off by an encircling score line, said severable portion being formed with a projecting shoulder extending around its upper periphery and providing engagement for a prying tool used in opening the container by a breaking along said score line, this severance of the cover part leaving a projecting rim at the base of said shoulder, said rim being engageable in the opening surrounding the broken score line to permit use of the severed portion as a reclosure.

JOHN M. HOTHERSALL. 30
